UNITED STATES PATENT OFFICE.

GOTTHOLD HILDEBRANDT, OF SPANDAU-TIEFWERDER, NEAR BERLIN, GERMANY,
ASSIGNOR TO AMERICAN INDUSTRIAL GAS COMPANY, OF NEW YORK, N. Y., A
CORPORATION OF NEW YORK.

PROCESS OF LIQUEFYING GASES WITH LOW BOILING-POINT.

1,199,701.

Specification of Letters Patent. Patented Sept. 26, 1916.

Original application filed January 9, 1911, Serial No. 601,614. Divided and this application filed June 11, 1914. Serial No. 844,525.

To all whom it may concern:

Be it known that I, GOTTHOLD HILDEBRANDT, engineer, citizen of Germany, subject of the King of Prussia and Emperor of 5 Germany, residing at Spandau-Tiefwerder 29^b, near Berlin, in the Kingdom of Prussia and Empire of Germany, have invented new and useful Improvements in Processes of Liquefying Gases with Low Boiling-Point, 10 of which the following is a specification.

The liquefaction of gases with a low boiling point has heretofore generally been effected only by the regenerative method indicated by Siemens in the year 1857 which 15 consists in compressing, cooling and expanding these gases such for example as nitrogen, oxygen, hydrogen, etc., and conducting the cooled gases thus obtained in counter current to fresh compressed gases, 20 thereby producing an interchange of heat, which ultimately results in the desired liquefaction. In accordance with various systems this expansion has taken place either in a counter current system of pipes or in open 25 cavities. This method has presented the defect that the liquefying period occupies a considerable time as the greatest cooling which is theoretically possible cannot be reached owing to the apparatus employed, 30 because with this method of expanding, the fractional resistances of the counter current system of piping do not permit of fully utilizing the energy supplied in the compressed gases, and by this method it is im- 35 possible to utilize the kinetic energy of the gas molecules obtained by expanding to such an extent that their pressure falls below atmospheric pressure after the expansion.

It is well known that compressed gas when 40 it issues through an aperture into a space of less pressure and escapes with an increased kinetic energy, is cooled close to the discharge aperture. This cooling (called by Travers "velocity cooling") has not been 45 used up to the present time for the liquefaction or the separation of gas although it represents a very rich source of cold because this cooling exists only immediately after passing through the aperture and disappears 50 at a relatively short distance from the aperture, the velocity of the stream of gas being reduced by friction caused by its impinging against the wall of the vessel into which it

flows. Therefore in order to produce low temperatures cooling by utilizing the Joule-Thompson effect only was applied which is the result of the internal work only caused by the expanding gas. 55

I have now succeeded in utilizing the velocity cooling for the continuous cooling and liquefaction of gases and the separation of gas mixtures by expanding the compressed and cooled gas through an expansion valve into a space or expansion nozzle of gradually increasing sectional area so proportioned 60 that the expansion takes place substantially adiabatically. By the use of suitably constructed and proportioned expansion nozzles into which the gases are thus expanded, the loss of energy of the existing systems is 65 avoided or minimized. These nozzles have a gradually increasing cross-sectional area, and may be of the type evolved by Laval, the smallest and the largest cross sections of 70 these nozzles presenting such differences, and 75 the increase from the one to the other being so proportioned that the expanded gas in the nozzle chamber itself may fall below the pressure of the atmosphere. In such nozzles 80 the expansion of the gas approximates adiabatic expansion, and except for slight losses by conduction may be considered as substantially adiabatic. The process of the 85 present invention may accordingly be considered as an adiabatic or substantially adiabatic expansion through an expansion nozzle into a space of gradually increasing sectional area whereby the velocity cooling may be utilized and this velocity energy 90 made to assist in the cooling and liquefaction. 90

In the accompanying drawings are shown certain forms of apparatus in which the process of the present invention can be carried out. 95

In the accompanying drawings Figure 1 represents a longitudinal section of a simple form of apparatus embodying this invention; Fig. 2 is a similar view of another form with a device for transferring the cold 100 to the compressed gas; Figs. 3 and 4 represent similar views of another form of the apparatus with an enlarged inlet space, a part of Fig. 4 being broken off for convenience in illustration. 105

In the apparatus illustrated the prelimi-

narily cooled compressed gas passes through the tube A and expansion valve B into the nozzle C. The nozzle C has a conical form of gradually increasing sectional area.

5 Taking the admission pressure of the preliminarily cooled compressed gas by way of example as 100 atmosphere equal to 100 kg. per square cm. and the admission aperture A of the nozzle C as 1 square mm. the velocity increases in correspondence with the diminishing pressure in the nozzle. The molecules then separate more and more from each other and when the width of the opening of the nozzle has reached 40 mm. that is 10 to say presents a ratio to the admission aperture of 1 to 1250, the pressure of the gas has fallen to 800 grams per square cm., that is to say to a minus pressure of somewhat more than one-fifth of an atmosphere. 15 It is therefore important that the lower aperture as compared with the upper aperture of the nozzle should have a substantially larger cross section. The increase in cross section may be so large that starting 20 at any desired initial pressure the gas is able to expand to atmospheric pressure and below. When applying a nozzle of this construction there is a minus pressure in the gas itself which accelerates its liquefaction. 25 30 By the conversion of the gas pressure into the extremely high velocities obtained by nozzle expansion a larger expenditure of external work is required so that the corresponding heat equivalent disappears and as the process takes place almost adiabatically this is only at the cost of the temperature of a part of the expanded gas.

Rankine has already shown that the adiabatic expansion of superheated steam causes 40 its condensation and in the Laval nozzle a highly heated liquid is converted by cooling into a mixture of liquid and vapor. The present invention is based on similar physical principles. In the first place the 45 specific heat of the expanded gas and the partitions is consumed to cover the expenditure of heat, then as soon as the pressure falls below atmospheric pressure a part of the gas must yield up its latent heat, that is to say it liquefies, but at first these liquid 50 particles retain the velocities of the former gas molecules exactly like the steam condensate of a steam generator feed injector. It is an advantage of the system that this reduction of pressure below atmospheric pressure 55 takes place merely by an increase of the velocity of the molecules without the necessity for special air pumps. Thus it is possible to cause the nozzles to open into a 60 collecting nozzle E (Fig. 2) or a collecting tube and to convert the velocity into pressure without risk of the liquid obtained again vaporizing.

It is of course necessary by suitably forming 65 the nozzle to prevent any friction of

the gas at the nozzle walls when the gas passing therethrough is under high pressures. For this purpose the portion of the nozzle near its inlet end is enlarged, as diagrammatically shown in Figs. 3 and 4. At 70 the inlet of the gas the expansion reservoir is enlarged to a cylindrical space G so that the jet of the gas issuing from the valve B or the like does not touch the walls. In consequence of injector action or suction a 75 vacuum is formed at the outer ends H of the enlarged space G, which assists the cooling action. A purely adiabatic expansion is not possible because the metallic nozzle and the supply pipe conduct their heat to 80 the expanded gas. In order to avoid this defect the cold imparted to the expansion valve B is transferred by a device shown in Fig. 2 directly to the compressed gas before the expansion and not only cools it, 85 but its property of being a poor conductor of heat is utilized for surrounding the expansion nozzle with a gas envelop which is a poor conductor. With this object the nozzle C is made of a substance which is a 90 good conductor such as copper, and inserted in a vessel D which receives the cooled compressed gas from the inlet (A). From the vessel D the cooled compressed gas is conducted to the expansion valve B, from which 95 it is expanded into the conical nozzle C. This apparatus can be similarly utilized for separating any foreign gases with a high boiling point from the compressed gas to be liquefied before it can exert any harmful effect by stopping the valve. The cooling which takes place during the expansion 100 process in the copper nozzle is consequently transferred directly to the compressed gas before its expansion and gradually cools it 105 sufficiently to cause the foreign substances of higher boiling point as for instance water-vapor, carbonic acid, etc., contained in the compressed gas to be precipitated as liquid or solid bodies which can be drawn 110 off through a special pipe F in the bottom of the vessel D.

It will be seen that in the process of the present invention the cold compressed gas is expanded through the expansion valve 115 into a nozzle of gradually increasing sectional area, the velocity of the expanded and partly liquefied gas being made use of to assist the cooling, and being so made use of that the pressure falls below atmospheric in the expansion chamber or nozzle, while a higher pressure may exist at a still greater distance from the expansion valve, as has been pointed out. When the compressed gas is subjected to the cooling effect 120 of the expanded gas the compressed gas is itself further cooled and loss of the cooling effect minimized. The energy of the expanded gas may be considered as converted 125 into the main cooling which causes the main 130

liquefaction and the velocity cooling which further assists and promotes this cooling.

I claim:—

1. The process of liquefying compressed and cooled gases having a low boiling point which comprises expanding such gases through an expansion valve without abrupt changes in direction and then causing the gas stream to assume a gradually increasing cross-sectional area of such proportions that velocity cooling of the expanded gas is effected.

2. The process of liquefying compressed and cooled gases having a low boiling point which comprises expanding such gases through an expansion valve into a chamber having a gradually increasing sectional area and so proportioned that velocity cooling of the expanded gas is effected, and bringing the compressed gas before expansion

into heat-interchanging relation with said chamber.

3. The process of liquefying compressed and cooled gases having a low boiling point which comprises expanding such gases from 25 a highly compressed and cooled condition through an expansion valve and causing the gas stream to assume a gradually increasing sectional area so proportioned that the expanding gases by their velocity reach a 30 lower pressure than that of the discharge receptacle, whereby velocity cooling of the gases is effected.

In testimony whereof I have hereunto set my hand in the presence of two subscribing 35 witnesses.

GOTTHOLD HILDEBRANDT.
